ATTORNEY.

UNITED STATES PATENT OFFICE.

JEROME G. HARRISON, OF PHILADELPHIA, PENNSYLVANIA.

LIFTING-JACK.

1,389,504.

Specification of Letters Patent. Patented Aug. 30, 1921.

Application filed July 18, 1919. Serial No. 311,734.

To all whom it may concern:

Be it known that I, JEROME G. HARRISON, a citizen of the United States, residing at Philadelphia, in the county of Philadelphia 5 and State of Pennsylvania, have invented new and useful Improvements in Lifting-Jacks, of which the following is a specification.

The invention relates to lifting jacks and 10 more particularly to that class of jacks known as screw jacks and has for an object to provide a lifting jack which can be easily operated to lift or jack up heavy loads with the least amount of energy and a minimum 15 amount of friction.

Among other features the invention comprehends a lifting jack in which use is made of a screw and a nut adapted to jack up or raise a load upon the application of power 20 to the screw, the relation of the nut to the screw being of a ball-bearing nature.

Still further the invention comprehends a lifting jack having a suitable handle and operating mechanism, with the handle adapted to be arranged in a compact out of the way position when the jack is not in use and readily positioned to permit of applying energy to the jack proper to accomplish the desired result.

30 In the further disclosure of the invention, reference is to be had to the accompanying drawings, constituting a part of this specification, in which similar characters of reference denote corresponding parts in all the 35 views, and in which,—

Figure 1— is a vertical sectional view taken through the jack and parts of the accompanying handle and operating mechanism.

40 Fig. 2— is a horizontal sectional view taken on the line 2—2 in Fig. 1.

Fig. 3— is a rear elevation of the nut with parts being broken away to disclose the underlying structure.

45 Fig. 4— is a horizontal sectional view taken on the line 4—4 in Fig. 3, and

Fig. 5— is a horizontal sectional view taken on the line 5—5 in Fig. 3.

Referring more particularly to the views, 50 I provide a base 10 carrying a suitable housing 11, the lower part of which may be in the form of a casting and the upper part 11^a of which is partially cylindrical and may be made of sheet metal or the like. The base 55 10 is formed with a lower race 12, preferably

made by machining the floor of the base and disposed within the lower part of the housing is a toothed wheel 13 having the teeth 14 thereof projecting to one side of the upper face, the opposite face of the wheel being 60 formed to provide an upper race 15 which together with the lower race 12 and suitable balls 16 arranged between the races, provides a ball-bearing support for the toothed wheel 13. Disposed within the housing 11 65 is a screw 17 having square threads 18, the said screw being set upon the central portion of the toothed wheel 13 with the latter rigidly secured to the screw by a suitable machine screw 19 or the like. The screw 17 70 carries an encircling nut 20, the latter being preferably formed of a plurality of parts or sections 21, 22, including an oblique portion 23 providing a passage-way 24 for a number of balls 25 adapted to be disposed in the passage-way 24 and in passages 26, both of which communicate with the passage-way 24, one at the upper end and the other at the lower end thereof, the one constituting the in-going passage-way and the other the out-going or return passage-way, with the balls 75 also arranged in the threads 18 of the screw which are encompassed by the nut. Thus in the operation of the screw and the resulting action of the nut, the balls in the in-going, 80 out-going and oblique passage-ways will be constantly moving therethrough and around the threads of the screw encircled by the nut, thereby reducing to a minimum, the friction 85 which otherwise would take place between the screw and the nut in the relative action 90 thereof if the balls were not provided. By having the passage-way 24 extending obliquely with the in-going and out-coming 95 passage-ways 26 tangential to the periphery of the screw proper, any possible chance of jamming of the balls between the screw and the nut is prevented. It will of course be understood that instead of the balls shown 100 and described any other form of anti-friction devices such as rollers or the like, may be employed.

Encircling the screw 17 is a tubular upright 27, the lower end of which may be suitably connected with the nut or form an 105 integral part thereof, as the case may be, said upright extending upwardly beyond the upper part 11^a of the housing and carrying a shoe 28 with a suitable guide ring 29 secured or formed with the upper part of the 110

housing to closely encircle the upright and aid in guiding the same in its vertical movement, preventing very little if any lateral play.

- 5 It will now of course be apparent that when the toothed wheel 13 is rotated on the ball-bearing of the base, resultant rotation of the screw 17 will take place and therefore the nut and its accompanying upright 27 10 will be raised to lift or jack up any load placed upon the shoe 28 with the ball-bearing construction between the nut and screw eliminating friction to a great extent and it will of course also be clear that the reversal of 15 the rotation of the toothed wheel 13 will cause the nut to descend and therefore bring with it the upright and accompanying shoe 28. To provide for the ready rotation of the toothed wheel 13, I employ a crank handle 20 including a crank 31 and a stem 32, the latter being preferably made in a plurality of sections 32^a, 32^b, which can be disjointed to permit of easily taking the handle away when the jack is not in use. The section 32^a 25 furthermore, is provided with a plurality of hinged portions 33, enabling the handle to be swung to any desired angle relative to the horizontal supporting the base and also permitting of the handle to be swung in an oblique plane, thereby to a great extent simulating a universal joint construction. The lower end of the handle, namely the section 32^b has one of these hinges provided at the juncture thereof with a stem 34 of a pinion 35, suitably journaled in the housing 11 and meshing with the teeth 14 of the toothed wheel or gear 13, said stem 34 having a flattened portion 36 immediately adjacent the exterior of the housing, which flattened portion 40 carries a ratchet wheel 37 normally engaged by a spring actuated pawl 38 mounted to swing on the housing 11 and having connected therewith a suitable wire 39, extending longitudinally along the stem 32 of the 45 handle to connect with a handled operating element 40, including collars 41 loosely encircling the stem 32 with a cross pin 42 through the stem to limit the downward sliding movement of the operating element, the 50 crank 31 limiting the upward sliding movement thereof. It will now be apparent that the pawl 38 normally engaging the ratchet wheel 37 will prevent reversal of movement of the handle in order that a load which has been jacked up can be held in its raised position 55 whereas operation of the element 40, involving the sliding thereof upwardly along the stem, will disengage the pawl 38 from the wheel 37 thereby permitting of reversing the operation of the crank handle, thus 60 lowering the jack.

It will of course be readily seen that the nut 20 is prevented from rotating because of

the particular shape of the nut and the particular configuration in cross section of the upper part 11^a of the housing 11, the nut as a unit providing an extension or projecting portion 20^a which might be said to be squared and forms the oblique part 23 providing the passage-way 24, while the upper part 11^a of the housing also has a squared portion 11^b which receives the squared portion or extension of the nut thereby preventing rotation of the latter relative to the former.

From the foregoing description it will be seen that the jack described provides a structure which will be capable of lifting great weights or loads with comparative ease and that very little energy on the part of the operator is required to bring about the desired result, the handle of the jack furthermore being so formed that it can be readily removed from connection with the jack proper so that the entire structure can be easily stored away in a small space when not in use.

Having described my invention, I claim—

1. In a jack the combination with a base and a gear revolvably supported in the base, of a screw carried by the gear and revolvable therewith, a nut encircling the screw, anti-friction elements carried by the nut and movable into and out of rolling contact with the threads of the screw when the nut is advanced or retracted on the screw, an upright carried by the nut, a shoe on the upright, a housing extending upwardly from said base, a handle, a pinion journaled in the base and meshing with said gear, pawl and ratchet mechanism on the gear and associated with the handle for locking the gear against reverse movement and means on the handle for moving said pawl and ratchet mechanism into and out of operating position.

2. In a screw operated pressure producing device the combination with a revolvable screw and an upright, of a housing for the upright and including an offset portion, means for actuating the screw and a nut supporting the upright and inclosed by the housing, said nut having an off-set portion fitting the off-set portion of the housing to prevent rotation of the nut relative to the housing, said off-set portion of the nut having a straight diagonal passage way communicating with a plurality of end passage ways in turn having communication with the threads of the screw and anti-friction elements operating in the threads of the screw and through the passage ways of the nut.

In testimony whereof I affix my signature.

JEROME G. HARRISON.
